UNITED STATES PATENT OFFICE.

CHARLES HEADLEY, OF PARKERSBURG, WEST VIRGINIA.

CURTAIN-FIXTURE.

1,055,976.

Specification of Letters Patent.

Patented Mar. 11, 1913.

Application filed May 15, 1912. Serial No. 697,567.

To all whom it may concern:

Be it known that I, CHARLES HEADLEY, a citizen of the United States, residing at Parkersburg, in the county of Wood and State of West Virginia, have invented certain new and useful Improvements in Curtain-Fixtures, of which the following is a specification, reference being had to the accompanying drawings.

10 This invention relates to new and useful improvements in pole fixtures for window shades and curtains and has for its object to provide an inexpensive and reliable device whereby a shade and a curtain may be 15 both suspended from a single supporting structure.

Another object of the invention is to provide a shade and curtain bracket which consists of a single piece of sheet metal or other 20 suitable material.

Another object of the invention is to provide a fixture of this character which will possess advantages in points of efficiency and durability, is inexpensive of manufacture and at the same time is simple in construction and operation.

With the above and other objects in view the invention consists in the novel features of construction and in the arrangement and 30 combination of parts hereinafter more fully described, pointed out in the claim and shown in the accompanying drawings in which,

Figure 1 is an elevation of a window casing showing my improved fixture applied thereto; Fig. 2 is an edge elevation; and Fig. 3 is a rear perspective view.

In carrying out my invention I provide an elongated plate which is formed from a 40 single piece of sheet metal or other suitable material and bent at its intermediate portion as shown at 1, so that its ends are disposed in a plane at right angles to each other. In the application of the device one 45 of the end portions 2 is disposed in a vertical plane, while the other end portion 3 is disposed in a horizontal plane.

The vertical end portion 2 is bent intermediate of its end as shown at 4, and curved slightly upwardly as shown at 50 5 to provide a suitable seat 6 for the curtain pole, the extreme end being secured to the casing by means of the screw 7. The horizontal end 3 of the plate is bent upon itself to form the outwardly extending bearing 8 55 for the pintle 9 of the shade roller 10, the extreme end of the portion 3 being securely fastened to the window casing by means of the screw 11, other suitable fastening means may be used in place of the screw 11 if 60 found desirable.

From the above description taken in connection with the drawing it will be readily apparent that I have provided a simple and durable device which can be manufactured 65 at an extremely low cost, and which provides a bracket formed on a single piece of sheet metal adapted for a support of both a curtain and a shade roller.

While I have shown and described the 70 preferred form of my invention it will be obvious that various changes in the details of construction and in the proportions may be resorted to for successfully carrying my invention into practice without sacrificing 75 any of the novel features or departing from the scope thereof.

What I claim is:—

A curtain fixture comprising a single piece of sheet metal bent at its intermediate 80 portion so that its ends are disposed in a plane at right angles to each other, one of said ends being bent upon itself and curved to form a seat for one end of the curtain pole, and the other of said ends being bent upon 85 itself to form an outwardly extending bearing for the pintle of a shade roller.

In testimony whereof I hereunto affix my signature in the presence of two witnesses.

CHARLES HEADLEY.
